US00D997380S

(12) **United States Design Patent** (10) **Patent No.:** **US D997,380 S**
(45) **Date of Patent:** **** Aug. 29, 2023**

(54) **ANALYSIS MACHINE**

(71) Applicant: **Beckman Coulter, Inc.**, Brea, CA (US)

(72) Inventor: **Nelson Garrido**, Miami, FL (US)

(73) Assignee: **BECKMAN COULTER, INC.**, Brea, CA (US)

(**) Term: **15 Years**

(21) Appl. No.: **29/786,616**

(22) Filed: **Jun. 1, 2021**

Related U.S. Application Data

(62) Division of application No. 29/688,131, filed on Apr. 18, 2019, now Pat. No. Des. 924,431.

(57) **CLAIM**

The ornamental design for an analysis machine, as shown and described.

DESCRIPTION

FIG. 1 is a front perspective view of an analysis machine showing my new design;

FIG. 2 is a front view thereof;

FIG. 3 is a top plan view thereof;

FIG. 4 is a right side view thereof;

FIG. 5 is a left side view thereof;

FIG. 6 is a rear view thereof; and,

FIG. 7 is a bottom plan view thereof.

The broken lines in the figures depict portions of the analysis machine that form no part of the claimed design; the broken lines form no part of the claimed design.

1 Claim, 7 Drawing Sheets
